UNITED STATES PATENT OFFICE.

SAUL ROBERT JACOBS, OF ALAMEDA, CALIFORNIA.

DESIGN FOR A CHARM, PIN, OR SIMILAR ARTICLE.

No. 39,116.

Specification for Design.

Patented Feb. 11, 1908.

Application filed January 10, 1908. Serial No. 410,313. Term of patent 7 years.

To all whom it may concern:

Be it known that I, SAUL ROBERT JACOBS, a citizen of the United States, residing at Alameda, county of Alameda, State of California, have invented a new, original, and ornamental Design for Charms, Pins, and Similar Articles, of which the following is a specification, reference being had to the accompanying drawing, forming a part thereof.

I claim:

The ornamental design for a charm, pin, or similar article, as shown.

In testimony whereof I have set my hand this 30th day of December A. D. 1907, in the presence of the two subscribed witnesses.

SAUL ROBERT JACOBS.
